UNITED STATES PATENT OFFICE.

HENRY DUFFY, OF WENATCHEE, WASHINGTON.

VACUUM SEALING DEVICE.

Application filed November 22, 1922. Serial No. 602,596.

To all whom it may concern:

Be it known that I, HENRY DUFFY, of Wenatchee, in the county of Chelan and State of Washington, have invented certain new and useful Improvements in Vacuum Sealing Devices; and I do hereby declare the following to be a full, clear, and exact description of the invention, such as will enable others skilled in the art to which it applies to make and use the same.

In Letters Patent No. 1,336,211 issued to me April 6, 1920, I have shown a vacuum sealing device by means of which a vacuum pump may be placed in communication with a space in which the air pressure is to be reduced, such as that existing in window sashes having two spaced apart panes.

My present invention is of the same general nature but it eliminates the valve seated in the lateral passage of the plug.

Figure 1 is a vertical sectional view. Figures 2, 3, 4 and 5 are details. The plug 1 is a hollow body threaded exteriorly as at 2 and adapted to be received by a double pane window sash or by a pipe having an inner pipe and an intermediate space from which the air is to be exhausted. This plug is intended to be inserted fully in an orifice in the sash, for instance, and to remain there without interfering with the movement of the sash as it does not project from the orifice.

In its bottom or inner end the plug is shown closed by a wall formed with a pair of holes 3 and a pair of upright pins 4 projecting from near its periphery. Above or inside of this wall is a disk valve 5 comprising a disk proper formed with holes 6 and having recesses or notches 7 in its periphery.

At its central portion the disk valve is provided with an up-standing blade 8. A screw 8^a is tapped in the bottom of the plug and extends into disk 5, preferably within the thickness of blade 8, to keep the disk in place.

By the construction thus far described the disk valve rests upon or in contact with the inner wall of the plug. By turning the blade 8 the holes 6 of the disk valve may be brought into register with holes 3 of the end wall of the plug. This turning of the disk valve is limited by its recesses 7 engaging pins 4 of the end wall. The construction may be so arranged that this engagement will occur when the holes 6 and 3 are in full register or completely out of alignment.

As appropriate means for turning the disk

valve I have shown a pump cylinder 9 to be inserted within the hollow plug and having oppositely disposed slots 10 to receive the blade 8. The piston rod 12 is flat or rectangular in cross section, as indicated at 13, and the opening in the outer end of the cylinder is of corresponding formation to receive it. Thus by turning the rod axially the cylinder is turned until the slots 10 slip over the blade. The further turning brings the holes of the disk valve into register with those of the inner wall of the plug. The pump may then be operated to exhaust the air from the space, after which a reverse turn will close the disk valve, and the pump may be withdrawn.

If it is desired to withdraw more air from the space between the window pane and the amount the pump cylinder will hold, the valve is closed by turning the pump cylinder, and the pump cylinder removed and the pump piston forced inwardly and the operation herebefore described repeated.

I claim as my invention:

1. The herein described sealing device comprising a hollow plug having an inner wall formed with holes, a disk valve in contact with the inner face of said wall and formed with holes, a pump to be inserted in said plug having a piston and cylinder adapted to interlock with said valve to move said holes into or out of register whereby the valve can be closed after the piston has withdrawn a certain amount of air through the valve.

2. The herein described vacuum sealing device comprising a hollow plug having an inner wall formed with holes, a disk valve in contact with the inner face of said wall and formed with holes and with an up-standing blade, a pump to be inserted in said plug having a cylinder formed with slots to receive said blade, means for turning said cylinder to move said holes into or out of register, and means for limiting such turning movement.

3. The herein described vacuum sealing device comprising a hollow plug and an inner wall formed with holes, a disk valve in contact with the inner face of said wall and formed with holes, a pump cylinder adapted to closely fit the inner wall of the hollow plug and having means interlocking with the valve to move said holes into or out of register, and means for limiting the turning movement of said valve.

4. The herein described vacuum device comprising a hollow plug having an inner wall formed with holes, a disk valve in contact with the inner face of said wall and formed with holes and with an up-standing blade, a pump to be inserted in said plug having a cylinder formed with slots to receive said blade, means for turning said cylinder to move said holes into or out of register, a pin carried by the inner wall of the plug near its edge and the disk valve having a recess in its periphery to engage said pin to limit the turning movement of the valve.
5. In testimony whereof I have signed this specification.

HENRY DUFFY.
